Primary Examiner — Michael C Stout*Assistant Examiner* — James T Tyree*(74) Attorney, Agent, or Firm* — Justin Lampel(57) **CLAIM**

The ornamental design for a toy train as shown and described.

DESCRIPTION

FIG. 1 is a perspective view of a toy train showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area 9 shown in FIG. 1;

FIG. 10 is an enlarged view of area 10 shown in FIG. 1;

FIG. 11 is an enlarged view of area 11 shown in FIG. 2;

FIG. 12 is an enlarged view of area 12 shown in FIG. 2; and,

FIG. 13 is an enlarged view of area 13 shown in FIG. 3.

The evenly-spaced broken lines show portions of the toy train that form no part of the claimed design; the dash-dot-dash broken lines represent enlarged sectional designations that form no part of the claim.
